CLAIM

We claim the ornamental design for an ultraviolet emitting device for nail hardening, as shown and described.

DESCRIPTION

FIG. 1 is a perspective view of the ultraviolet emitting device for nail hardening showing our new design;
FIG. 2 is a front view thereof;
FIG. 3 is a rear view thereof;
FIG. 4 is a left side view thereof;
FIG. 5 is a right side view thereof;
FIG. 6 is a top (plan) view thereof; and,
FIG. 7 is a bottom view thereof.
